SNOW SKATE

Robert Michael King, Downsview, Ontario, Canada, assignor to Tel-Pro Products Limited, Toronto, Ontario, Canada

Filed Jan. 9, 1973, Ser. No. 322,118

Term of patent 14 years

Int. Cl. D21—02
U.S. Cl. D34—14 D

Fig. 1.

Fig. 2.

FIG. 1 is a top perspective view of a snow skate showing my new design;

FIG. 2 is a bottom plan view thereof;

FIG. 3 is a side elevational view;

FIG. 4 is a sectional view taken on the line 4-4 of FIG. 3; and

FIG. 5 is a rear elevational view.

I claim:

The ornamental design for a snow skate, as shown and described.
